ADJUSTABLE TUMBLER LOCK

Leo E. Deutsch, Hammond, Ind., assignor to
Marshall William Deutsch, Hammond, Ind.Application April 23, 1934, Serial No. 722,011
Renewed April 13, 1936

17 Claims. (Cl. 70—70)

The invention relates to a lock and more especially to an adjustable tumbler lock.

The primary object of the invention is the provision of a lock of this character, wherein the turning barrel and the casing of the lock have fitted therein tumblers, these being of novel construction and arrangement and operated through actuator bars controlled by a special key, so that it is required, before the lock can be actuated, that the key be set in conformity with the combination of the lock, this latter being changeable at the option of the user of the lock, thereby making it impossible for one other than the rightful user to actuate the lock for the unlocking of the same.

Another object of the invention is the provision of a lock of this character, wherein the barrel is fitted within the casing in a novel manner so that it can be conveniently removed for the changing of the combination of the lock at the option of the user thereof, the barrel being constructed to accommodate actuator bars which control the tumblers of the lock for the manipulation thereof through the use of a special key, the lock being safe and in its construction being novel in entirety.

A further object of the invention is the provision of a lock of this character which is comparatively simple in construction, thoroughly reliable and efficient in its operation, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

40 In the accompanying drawings:

Fig. 1 is a perspective view of a lock, with parts broken away, constructed in accordance with the invention.

45 Figure 2 is a horizontal longitudinal sectional view of the lock.

Figure 3 is a fragmentary sectional view on the line 3—3 of Figure 2.

50 Figure 4 is a fragmentary vertical longitudinal sectional view.

Figure 5 is an exploded perspective view of the actuator bars as employed in the lock.

Figure 6 is a perspective view of the key as employed for operating the lock.

55 Similar reference characters indicate corre-

sponding parts throughout the several views in the drawings.

Referring to the drawings in detail, the lock comprises a cylindrical casing 10 open at opposite ends and at one end there is formed an internal annular flange 11 for the interfitting with the casing of a rotatable head 12, the latter having an extension 13 for connection with a bolt or other locking medium on the turning of said head. It is required, for the interfitting of the head 12 with the casing 10, that the latter be longitudinally split and thereafter when the head has been interfitted the split sections of the casing are welded or otherwise united permanently.

Insertable through the opposite open end of the casing 10 is a turning barrel 14, having a flat face coupling extension 15 for reception in a correspondingly shaped opening 16 in the head 12 so that when the barrel is turned or rotated the said head 12 will turn or rotate therewith. The front or outer end of the barrel 14 has a disk-like head 17 which is of a diameter corresponding approximately to the diameter of the casing 10 so as to overlie the said casing at the outer open end thereof.

The barrel 14 has provided centrally therein a keyway or slot 18 for accommodating a key 19, this being of a permutation type having displaceable bits 20 operated from a trigger 21 which projects the said bits to operative position according to the combination or set permutation of the lock proper for the actuation thereof or the turning of its barrel 14.

The barrel 14 has fitted therewith a removable section 22 and this section carries a lug 23 which matches an annular groove or channel 24 in the inner surface of the casing 10, so that when the lug 23 is engaged in the groove or channel 24 the barrel is free for rotation or turning in the said casing and the said barrel cannot be withdrawn or taken out of the casing.

To permit the removal of the barrel 14, the inner surface of the casing, at a selected point, has formed therein a longitudinally extending channel or groove 25 which extends through the outer or forward open end of said casing, and the lug 23 can be brought to a position to register with this channel or groove 25 and in so doing the barrel 14 can be withdrawn or taken out of the casing. The purpose of taking out the barrel 14 from the casing 10 is to change the combination or permutation of the lock at the option of the user.

Interfitted with the casing 10 and the barrel 14 are rotatable tumblers, these being arranged in pairs at diametrically opposite sides of the barrel

14, and the tumblers of each pair are spaced from each other and are positioned at right angles to the longitudinal axis of said barrel. Each tumbler is formed of two sections 26 and 27, respectively, their separation from each other being in conformity with the circular separation of the casing 10 and barrel 14. The section 27 is provided with a dovetailed rib 28 (Fig. 31) fitting a dovetailed groove 29 in the casing 10, so that the section 27 is rotatably interfitting with the casing 10 to prevent this section 27 from dropping out of the casing when the barrel 14 is removed from the latter. The section 26 is provided with a wing or extension 30 which is adapted to be projected into the path of a permutation or combination lug 31 on the associated one of a group of actuator bars 32, these being slidably fitted in the keyway or slot 18. The bars 32 carry guide pins 33 about which are arranged coiled expansion springs 34 (Fig. 2) fitted within seats 35 in the barrel 14, and these springs urge the actuator bars in a forward or outward direction within the way or slot 18 to be operated upon by the key 19 when the latter is engaged or inserted in the way or slot 18 for the operation of the lock. The section 22 removable from the barrel 14 when the latter is extracted or taken out of the casing 10 permits access to be had to the bars 32, so that they can be rearranged for the alteration or changing of the combination or permutation of the lock at the will of the user of the latter.

Mounted in the barrel 14 between the tumblers or the sections 26 and 27 thereof are coiled springs 36, these being attached to the sections 26 and 35 operating to project the extensions 30 thereof into the path of the lugs 31 of the actuator bars 32, so that the tumblers can be turned under movement of the said bars 32 to free the barrel 14, whereby it may be turned or rotated within the casing 10 for the actuation of the lock, the actuator bars 32 being controlled and operated by the key 19.

Normally the fore tumblers of the pairs as contained within the casing and barrel 10 and 14 of the lock have their sections 26 and 27 positioned so as to lie crosswise to the outer surface of the barrel 14 and thus lock the barrel against turning or rotating within the casing 10, while the other tumblers of the pairs, comprising those inwardly spaced from the ones before mentioned, are positioned so that the split or separation between the sections 26 and 27 will align with the separation between the casing 10 and barrel 14. These latter tumblers being thus disposed out of locking position, are moved to locking position by their associated actuator bars 32 should be erroneous key be inserted in the slot or way 18, thereby avoiding any possibility of fraudulent manipulation of the lock by the turning of the barrel 14 thereof should it happen that the key as employed under fraudulent manipulation permits the fore tumblers to turn to freeing position for the barrel 14.

Referring to Figure 2 of the drawings, the tumblers including the sections 26 and 27 are normally disposed as shown, and thus the barrel 14 is held against turning or rotation within the casing 10. Now, when the key 19 is set in conformity with the combination of the lock and inserted in the way or slot 18, the bits 20 of the key will displace those actuator bars 32 associated with the fore tumblers, permitting the fore tumblers to turn under the action of the springs 36 to freeing position for the barrel 14, while the aft tumblers will remain inactive by reason of the fact that the

wings 30 of the sections 26 and 27 of such tumblers will not be acted upon by the lugs 31 of the actuator bars 32, associated therewith. All the tumblers being thus freed the barrel 14 can be turned or rotated by the key 19 for actuating the lock.

Should an improper key be inserted in the barrel 14 through the slot 18, all of the actuator bars 32 which should be displaced rearwardly and all of those actuator bars which should not be moved, in order to set all of the tumblers 26, 27 in position to free the barrel 14, will not be displaced or be unaffected, respectively, and any actuator bar associated with a fore tumbler which is not moved, or any one associated with a rear tumbler which is moved will either leave a fore tumbler in locking position or move a rear tumbler to locking position to prevent turning of the barrel 14 within the casing 10.

The actuator bars 32 normally are in the position as shown in Figure 2 of the drawings and thus the barrel 14 is held against turning or rotating within the casing 10, such movement of the barrel being had only by using the key 19 with its bits 20 set in conformity with the requirements of the combination of the lock, whereupon the tumblers, including the sections 26 and 27, will be affected by the actuator bars 32 for the freeing of the barrel 14 for its rotation or turning within the casing 10. Such movement of the barrel 14, through the agency of the extension 15 thereof, will rotate the head 12 and its extension 13 to move the usual bolt or other locking medium (not shown). In addition, movement of all of the tumblers 26, 27 to their freed position will permit the turning of the barrel 14 within the casing 10 to bring the lug 23 into register with the longitudinal groove 25, whereupon the barrel may be withdrawn forwardly from the casing. The section 22 of the barrel 14 may then be removed to permit the actuator bars 32 to be selectively rearranged to change the permutation action thereof as desired. With this arrangement, the bits 20 of the key 19 may be readjusted, as disclosed in Letters Patent No. 2,019,399, issued to me on October 29, 1935, to properly co-operate with the new combination set in the lock.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is:

1. A lock of the kind described comprising a cylindrical casing, a barrel rotatably fitted in the casing, rotatable tumblers fitted with the barrel and casing for pinning said barrel against rotation within the casing, a plurality of actuator bars fitted within said barrel and coacting with the tumblers for disposing the same to release the said barrel with relation to the casing, said barrel having a keyway in the path of said actuator bars for receiving a key to operate the bars, and springs active with the tumblers to urge the same in a position for freeing the barrel within the casing.

2. A lock of the kind described comprising a cylindrical casing, a head rotatably interfitting with one end of the casing, a barrel rotatably

5 fitted in the casing and having coupling connection with said head, rotatable tumblers fitted with the barrel and casing for holding the latter within the casing, a plurality of actuator bars fitted within said barrel and coacting with the tumblers for disposing the same to release and hold the said barrel with relation to the casing, said barrel having a keyway in the path of said actuator bars for receiving a key to operate the 10 bars, springs active with the tumblers to urge the same in a position for freeing the barrel within the casing, a lug on the barrel for rotatably retaining the same within the casing and means for releasing the barrel from said casing.

15 3. A lock of the kind described comprising a cylindrical casing, a head rotatably interfitted with one end of the casing, a barrel rotatably fitted in the casing and having coupling connection with said head, rotatable tumblers operating within the barrel and casing for holding said barrel against rotation within the casing, a plurality of actuator bars fitted within said barrel and coacting with the tumblers for disposing the same to release the said barrel with relation 20 to the casing, said barrel having a keyway in the path of said actuator bars for receiving a key to operate the bars, springs active with the tumblers to urge the same in a position for freeing the barrel within the casing, a lug on the barrel for rotatably retaining the same within the casing, means for releasing the barrel from said casing, springs active against the actuator bars to hold the same 25 in a normal position for holding the barrel against movement within the casing, the said tumblers each being in two sections, means for interlocking one section of each tumbler with the casing.

25 4. A lock of the kind described comprising a cylindrical casing, a head rotatably interfitted with one end of the casing, a barrel rotatably fitted in the casing and having coupling connection with said head, tumblers for rotatably operating within the barrel and casing at right angles to the longitudinal axis of the said barrel for holding the latter within the casing, a plurality of actuator bars fitted within said barrel and coacting with the tumblers for disposing the same to release and hold the said barrel with relation to the casing, said barrel having a keyway in the path of said actuator bars for receiving a key to operate the bars, springs active with the tumblers to urge the same in a position for 30 freeing the barrel within the casing, a lug on the barrel for rotatably retaining the same within the casing and for releasing the barrel from said casing, and springs active against the actuator bars to hold the same in a normal position for latching the barrel against movement within the casing.

35 5. A lock of the kind described comprising a cylindrical casing, a head rotatably interfitted with one end of the casing, a barrel rotatably fitted in the casing and having coupling connection with said head, tumblers for rotatably operating within the barrel and casing at right angles to the longitudinal axis of the said barrel for holding the latter within the casing, a plurality of actuator bars fitted within said barrel and coacting with the tumblers for disposing the same to release and hold the said barrel with relation to the casing, said barrel having a keyway in the path of said actuator bars for receiving a key to operate the bars, springs active with the tumblers to urge the same in a position for 40 freeing the barrel within the casing, a lug on the barrel for rotatably retaining the same within the casing and for releasing the barrel from said casing, and springs active against the actuator bars to hold the same in a normal position for latching the barrel against movement within the casing.

45 6. A lock of the kind described comprising a cylindrical casing, a head rotatably interfitted with one end of the casing, a barrel rotatably fitted in the casing and having coupling connection with said head, tumblers for rotatably operating within the barrel and casing at right angles to the longitudinal axis of the said barrel for holding the latter within the casing, a plurality of actuator bars fitted within said barrel and coacting with the tumblers for disposing the same to release and hold the said barrel with relation to the casing, said barrel having a keyway in the path of said actuator bars for receiving a key to operate the bars, springs active with the tumblers to urge the same in a position for 50 freeing the barrel within the casing, a lug on the barrel for rotatably retaining the same within the casing and for releasing the barrel from said casing, and springs active against the actuator bars to hold the same in a normal position for latching the barrel against movement within the casing, the said tumblers each being in two sections, means for interlocking one section of each tumbler with the casing, a removable section in the barrel for permitting access to the actuator bars for selective rearrangement thereof for changing permutation action of the same.

55 7. A lock of the kind described comprising a cylindrical casing, a head rotatably interfitted with one end of the casing, a barrel rotatably fitted in the casing and having coupling connection with said head, tumblers for rotatably operating within the barrel and casing at right angles to the longitudinal axis of the said barrel for holding the latter within the casing, a plurality of actuator bars fitted within said barrel and coacting with the tumblers for disposing the same to release and hold the said barrel with relation to the casing, said barrel having a keyway in the path of said actuator bars for receiving a key to operate the bars, springs active with the tumblers to urge the same in a position for 60 freeing the barrel within the casing, a lug on the barrel for rotatably retaining the same within the casing and for releasing the barrel from said casing, and springs active against the actuator bars to hold the same in a normal position for latching the barrel against movement within the casing, the said tumblers each being in two sections, means for interlocking one section of each tumbler with the casing, a removable section in the barrel for permitting access to the actuator bars for selective rearrangement thereof for changing permutation action of the same, and a disk-like head formed on the barrel and of a diameter equal to the diameter of the casing to overlap the same at its front end.

65 8. A lock of the kind described comprising a cylindrical casing, a rotatable barrel fitted in said casing, spring tensioned tumblers at one side of the barrel and housed by both the barrel and casing and rotatable on axes at right angles to the longitudinal axis of the latter for holding said barrel fixed, and a plurality of actuator bars independently slideable longitudinally of said barrel and coacting with the tumblers to release the said barrel with relation to the casing.

70 9. A lock of the kind described comprising a cylindrical casing, a head rotatably interfitted with one end of the casing, a barrel rotatably fitted in the casing and having coupling connection with said head, tumblers for rotatably operating within the barrel and casing at right angles to the longitudinal axis of the said barrel for holding the latter within the casing, a plurality of actuator bars fitted within said barrel and coacting with the tumblers for disposing the same to release and hold the said barrel with relation to the casing, said barrel having a keyway in the path of said actuator bars for receiving a key to operate the bars, springs active with the tumblers to urge the same in a position for 75 freeing the barrel within the casing, a lug on the barrel for rotatably retaining the same within the casing and for releasing the barrel from said casing, and springs active against the actuator bars to hold the same in a normal position for latching the barrel against movement within the casing.

casing, a rotatable barrel fitted in said casing, spring tensioned tumblers at one side of the barrel and housed by both the barrel and casing and rotatable on axes at right angles to the longitudinal axis of the latter for holding said barrel fixed, and a plurality of spring tensioned actuator bars independently slideable longitudinally of said barrel and coacting with the tumblers to release the said barrel with relation to the casing, said barrel having a keyway in the path of said actuator bars for receiving a key to operate the bars.

10. A lock of the kind described comprising a casing, a barrel rotatably fitting said casing, tumblers disposed crosswise between and rotatably interfitting the casing and barrel at opposite sides of the latter for holding the said barrel against rotation, and means confined within the barrel and slideable longitudinally of the same to free the barrel for rotation within the casing.

11. A lock of the kind described comprising a casing, a barrel rotatably fitting said casing, tumblers disposed crosswise between and rotatably interfitting the casing and barrel at opposite sides of the latter for holding the said barrel against rotation, and means confined within the barrel and slideable longitudinally of the same to free the barrel for rotation within the casing, said barrel having a keyway in the path of said means for receiving a key to operate the same.

12. In a lock of the kind described, a bolt actuating barrel rotatably supported, substantially cylindrical shaped sectional tumblers disposed crosswise of the barrel and housed in both the latter and a casing therefor for turning on axes at right angles to the longitudinal axis of the barrel for holding the said barrel fixed, and actuator means confined within the barrel and slideable longitudinally of the same to free said barrel for its rotation.

13. In a lock of the kind described, a bolt actuating barrel rotatably supported, rotatable tumblers disposed crosswise of the barrel and turning on axes at right angles to the longitudinal axis of the barrel for holding the said barrel fixed, actuator means confined within the barrel for actuating the tumblers to free said barrel for its rotation, and a plurality of actuator bars fit-

ting the barrel and movable longitudinally thereof and coacting with the tumblers to permit release of said barrel for rotation thereof.

14. In a lock of the character described, a rotatable releasing barrel, a sectional cylindrical shaped tumbler rotatably supported crosswise of said barrel and movably housed for holding said barrel fixed, and means shiftable longitudinally of the barrel and coacting with said tumbler to free the barrel.

15. In a lock of the character described, a rotatable releasing barrel, a sectional cylindrical shaped tumbler rotatably supported crosswise of said barrel and movably housed for holding said barrel fixed, means shiftable longitudinally of the barrel and coacting with said tumbler to free the barrel, and means active upon the tumbler for normally maintaining it in position for holding the barrel fixed.

16. In a lock of the character described, a rotatable releasing barrel, a sectional cylindrical shaped tumbler rotatably supported crosswise of said barrel and movably housed for holding said barrel fixed, means shiftable longitudinally of the barrel and coacting with said tumbler to free the barrel, means active upon the tumbler for normally maintaining it in position for holding the barrel fixed, and a casing rotatably supporting said barrel and having a portion thereof for the interfitting of the tumbler therewith when the latter is in position for holding the barrel fixed.

17. In a lock of the character described, a rotatable releasing barrel, a sectional cylindrical shaped tumbler rotatably supported crosswise of said barrel and movably housed for holding said barrel fixed, means shiftable longitudinally of the barrel and coacting with said tumbler to free the barrel, means active upon the tumbler for normally maintaining it in position for holding the barrel fixed, and a casing rotatably supporting said barrel and having a portion thereof for the interfitting of the tumbler therewith when the latter is in position for holding the barrel fixed, the said barrel having a keyway for receiving a key for actuating said means.
